UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TRANSMISSION CIRCUITS.

Application filed September 30, 1922. Serial No. 591,486.

To all whom it may concern:

Be it known that I, JOSEPH W. HORTON, a citizen of the United States, residing at Bloomfield, in the county of Essex, State 5 of New Jersey, have invented certain new and useful Improvements in Transmission Circuits, of which the following is a full, clear, concise, and exact description.

This invention relates to transmission circuits and has for one object the provision 10 of a testing circuit which will enable an observer to obtain indications of various types of an electrical characteristic subject to variations. Further objects will appear hereinafter.

In the form of this invention hereinafter described in detail these objects are accomplished by an arrangement which may be employed, for example, in testing the 20 strength of the transmission currents in a signaling line, either by a telephone receiver or by a direct current measuring instrument. The arrangement consists, briefly in one or more vacuum tube amplifiers or other amplifying devices, connected across the line, a 25 characteristic of which is to be tested. The output of the amplifier by a non-inductive coupling is connected to the input terminals of a vacuum tube rectifier or a detector, the 30 output circuit of which includes a direct current measuring instrument. Bridged across the input terminals of the rectifier is the high impedance winding of a transformer, the low impedance winding of which is connected to an alternating current translating 35 device, such as a telephone receiver. The combined arrangement therefore may be employed for giving both audible and visible indications of the strength of the signaling 40 currents in the line to which the amplifier is connected.

The drawing illustrates a combined amplifier-rectifier circuit embodying this invention.

Referring in detail to the drawing, a 45 transmission or signaling line 5, 5 is disclosed, and it will be assumed that it is desired to obtain both visible and audible indications of the strength of the signaling currents therein, in order to determine if satisfactory transmission is being maintained.

The testing arrangement of this invention comprises a vacuum tube amplifier 7, having 50 its input terminals 8 and 9 connected across

line 5, 5 by a step-up transformer 10, which 55 preferably should have such a transformation ratio that substantially no transmission loss is produced by this connection of the high impedance input circuit of tube 7 across the line. The output circuit of tube 7 includes between the anode 11 and cathode 60 9 the primary winding 12 of a transformer 13, the secondary winding 14 of which is connected to an alternating current translating device, such as a telephone receiver 15. 65 The primary winding 12 of this transformer is also included in the input circuit of a vacuum tube detector or rectifier 16, in the output circuit of which is a direct current measuring instrument 17, which may, for example, be a direct current milliammeter. A battery or other source of voltage 18 may be employed in series with the primary winding 19 of detector 16 sufficiently negative to reduce 70 the space current of the rectifier to zero, when no alternating current voltage is impressed on the detector from the amplifier 7. This arrangement makes it possible to 75 secure on the direct current meter 17, a deflection which is a function of the strength of the transmission currents in line 5, 5. If transformer 13 is so designed that winding 12 is of very high impedance, the connection 80 of the input electrodes of the detector 85 across the primary winding of this transformer will make it possible to secure this meter deflection with a very small loss in the A. C. output of the transformer. The secondary winding 14 of transformer 13 should 90 preferably be a low impedance winding so as to step down the impedance of the output circuit of tube 7 to the order of the impedance of the telephone receiver.

Space current for the two tubes, 7 and 95 16, is supplied from a common source of voltage 20, which is connected to anode 11 through a series retard coil 21, and which is connected to the anode of tube 16 through the meter 17. A heating current is supplied 100 to the two filaments by a suitable source of voltage 23. A condenser 24 may be employed to keep the direct current from source 20 out of the primary winding 12 of the transformer 13.

It is to be understood that the embodiment of this invention described above is capable of many and substantial modifica-

tions without departing in any wise from the spirit of this invention as defined in the appended claims.

The invention claimed is:

5. 1. In combination, a plurality of electric discharge devices connected in tandem, each comprising an anode, a cathode and a control electrode, means for connecting the first of said devices to an alternating current line, one of said devices being adjusted to operate as a rectifier, a direct current instrument responsive to the current rectified thereby, a high impedance transformer winding connected in shunt to the control electrode and cathode of said rectifier, and means for inductively connecting a telephone receiver to said winding.
- 10 2. Means for testing a signaling line comprising an amplifier having input and output terminals, said input terminals being so connected to said line to present a practically infinite impedance when viewed from said line, a vacuum tube rectifier having input and output terminals responsive to the currents amplified by said amplifier, a direct current measuring instrument connected to the output terminals of said rectifier for giving a visible indication of the strength of the signals in said line, a transformer having a high impedance winding connected across said rectifier input terminals, a low impedance winding for said transformer, and means connected to said low impedance winding for translating alternating current into energy of a different character.
- 15 3. Means for testing a signaling line comprising an amplifier having input and output terminals, a transformer for connecting said input terminals to said line, said transformer has a practically infinite impedance when viewed from said line, a vacuum tube detector comprising an anode, a cathode and a control electrode, a non-inductive connection between the output terminals of said amplifier and the control electrode and cathode of said detector, means for giving a visible indication of the strength of the signals detected by said detector, a high impedance transformer winding connected between said control electrode and said cathode, and means associated with the second winding of said transformer for giving an audible indication of the strength of the signals in said line.

4. Means for testing a signaling line comprising a vacuum tube amplifier having an anode, a cathode and a control electrode, a rectifier comprising an anode, a cathode and a control electrode, a step-up transformer for connecting the control electrode and cathode of said amplifier across said line, a connection including a condenser between the anode of said amplifier and the control electrode of said rectifier, a connection between said cathodes, a shunt path across said connections at a point on said first connection between said condenser and the control electrode of said rectifier, said shunt path comprising a high impedance transformer winding and a source of voltage, said source being of sufficient magnitude to reduce to zero the space current of said rectifier in the absence of alternating current signals in said line, a measuring instrument in the output circuit of said rectifier, a telephone receiver, and means for connecting said receiver to said high impedance winding.

5. Means for testing a signaling line comprising amplifying means having input and output terminals, means for connecting said input terminals to said line, a rectifier, connections between said output terminals and said rectifier, a high impedance transformer winding in shunt to said connections, a telephone receiver, means for coupling said receiver to said winding and a current measuring instrument responsive to the current rectified by said rectifier.

6. Means for testing a signaling line comprising an amplifier having input and output terminals, said input terminals being so connected to said line as to present a practically infinite impedance when viewed from said line, an outgoing alternating current line, a transformer having a high impedance primary winding connected to said output terminals and having a low impedance secondary winding connected to said outgoing line, a vacuum tube rectifier having electrodes connected across said primary winding and a direct current measuring instrument responsive to the current rectified by said rectifier.

In witness whereof, I hereunto subscribe my name this 27th day of September, A. D., 1922.

JOSEPH W. HORTON.
